CONNECTER DEVICE

Josiah B. Wisner, Camden, N. J.

Application August 10, 1935, Serial No. 35,641

9 Claims. (Cl. 173—263)

This invention relates to devices for connecting electrical conductors together, the principal object of the invention being to provide a novel device by means of which two insulated electrical conductors may be connected together rapidly and with a minimum of effort and without the necessity of removing any of the insulation from the conductors.

Another object of the invention is to provide a simple water-proof device which is small and compact and at the same time efficiently serves the purpose in view. The device is particularly adaptable for use in connection with electrical signaling systems, telephone systems and the like. It may be readily carried about and easily manipulated even under conditions of poor visibility such as at night.

A further and more specific object of the invention is to provide a simple device of this nature which comprises only two cooperative parts which may be very easily manipulated.

These and other objects of the invention, as well as the features thereof may be clearly understood from the accompanying drawing illustrating a preferred embodiment of the invention.

In the drawing:

Fig. 1 is a side elevational view of the assembled device;

Fig. 2 is a plan view of the device;

Fig. 3 is a sectional view taken through the device centrally thereof;

Fig. 4 is a side elevational view of one of the parts of the device;

Fig. 5 is a sectional plan view taken along line 5—5 of Fig. 4;

Fig. 6 is a plan view of the part shown in Fig. 4;

Fig. 7 is a sectional plan view illustrating the disposition of the conductors associated with the device; and

Fig. 8 is an enlarged sectional view of the assembled device showing a conductor associated therewith.

Referring to the several views of the drawing, the device comprises a pair of attachable parts 1 and 2, the part 1 comprising an outer casing 3 formed of insulating material, such as "Bakelite", and a member 4 seated snugly within and secured to the casing 3. The member 4 may be formed of any suitable metal, although it may be formed of any other material having the characteristics necessary for the operation described hereinafter. The edge of the cup-shaped casing 3 is flared outward, as at 5, for a purpose which will appear later. The inset member 4 preferably comprises a solid body 6 having a central threaded opening

7 and an annular tapered blunt edge 8 surrounding the central opening. Between the central opening and the annular blunt edge 8 there is provided a substantially flat annular surface 9. It will be seen that the solid body 6 projects out 5 of the casing 3, as shown clearly in Figs. 3 and 8.

The part 2 of the device comprises an outer cup-shaped casing 10 which is also formed of insulating material, such as "Bakelite". The annular edge of this casing is also flared outward 10 at 11 for a purpose which will appear presently. Within the casing 10, there is snugly seated and secured a cup-shaped metallic member 12 which carries a centrally located extending threaded shank 13 which is adapted for insertion in the 15 threaded opening 7 of the part 1. Spaced from the threaded shank and surrounding the same, there is provided an annular sharp edge 14. This edge is of slightly less diameter than the blunt edge 8, as shown in Figs. 3 and 8, to enable the 20 parts to cooperate in a manner described hereinafter. Adjacent the sharp edge 14, there is provided an annular recess 15, the purpose of which will be explained later.

The cylindrical wall of the metallic member 25 12 extends beyond the insulating casing 10, as shown clearly in Fig. 4 and the extended portion of the member 12 is provided with diametrically opposed openings 16 which are adapted to receive a pair of conductors from opposite sides of the 30 device, as shown in Fig. 7. Between the flared edge portions 5 and 11 of the insulating outer casings, and surrounding the extended portion of the metallic member 12, there is provided a loose composite washer which comprises a soft 35 rubber washer 17 cemented to a hard fiber washer 18 (see Figs. 3 and 8). When the parts of the device are screwed together, this composite washer occupies the annular space between the flared edges of the outer insulating casings, sealing the 40 said space against the admission of moisture. The fiber washer 18 is preferably slightly larger in diameter than the rubber washer 17 so that the composite washer may be manipulated and properly arranged by feel, thus facilitating the 45 use of the device under conditions of poor visibility.

The metal inset members 4 and 12 are preferably provided with integral projections or lugs on their outer cylindrical surfaces, as shown at 50 19 in Fig. 7, so that when the bakelite casings are molded about the inset members, such members are interlocked with and secured to their respective casings. The outer cylindrical surfaces of the casings 3 and 10 are preferably fluted, as 55

shown in Fig. 1, to facilitate tightening of the parts.

In using the device, the parts are separated and ends of the conductors to be connected together 5 are inserted through the openings 16 of the part 2 from opposite sides thereof, as shown in Fig. 7. Abutment of the ends of the insulated conductors with the central threaded shank 13 causes the conductor ends to take positions on opposite sides 10 of the screw shank, as shown in Fig. 7. It has been found that this takes place or may be easily caused to take place when diametrically opposed openings 16 are employed. But, if desired, the openings 16 may be slightly offset with respect to 15 one another to insure the disposition of the conductor ends illustrated. With the conductor ends thus positioned within the part 2, the composite washer is put into place with the soft rubber washer 17 engaging the conductors. The washer 20 is held down upon the conductors and serves to maintain them in place, while the part 1 is threadedly attached to the part 2 as clearly illustrated. As the part 1 is screwed into place, the washer and the flat annular surface of the flared 25 edge 11 grip the conductors, the insulation being flattened at that point, as shown in Fig. 8, and the soft rubber washer being compressed about the insulated conductor to form a moisture-proof seal. The hard fiber washer 18 serves as a backing 30 for the soft rubber washer and lengthens the life of the rubber washer. It will be seen that as the part 1 is screwed into place, the hard fiber washer is subjected to the friction occasioned by the turning of part 1 so that the soft rubber 35 washer is fully protected.

As the part 1 is screwed into place, the annular blunt edge 8 and the flat annular surface 9 force the conductors against the sharp edge 14, and the blunt edge 8 forces the conductors adjacent edge 40 8 into the annular recess 15 and jams the insulated conductors against the wall of member 12. It will be seen that a reverse bend or kink is put 45 in the conductors, as shown clearly in Fig. 8. The sharp edge 8 bites into the insulation of the conductors and contacts the conductor cores. Thus the conductors are electrically connected 50 through the metallic member 12. At the same time, the conductors are securely fastened within the device so that it is impossible to pull the conductors out of the device without separating the parts thereof.

It will be seen from the illustration and foregoing description that the device is simple in construction and may be made very small so that it 55 may be easily carried about. It will also be seen that the device may be easily manipulated and may be used to advantage in any instance where it is desired to rapidly connect two conductors together. Although a single preferred embodiment of the invention has been illustrated, it will be understood that various changes and modifications may be made within the scope of the invention as defined by the appended claims.

I claim:

1. A device for connecting insulated electrical conductors, comprising a cup-shaped part having openings in its side wall for the reception of said conductors, an annular sharp metallic projecting edge on said part located concentrically with respect to said side wall, whereby an annular recess is provided between said edge and said side wall, a second part attachable to said first part, and a recessed projection on said second part having an annular blunt edge adapted to enter said annular recess, whereby said conductors are pressed 60 against said sharp edge and are forced into said annular recess and wedged against said side wall when said parts are attached together.

2. A device for connecting insulated electrical conductors, comprising a cup-shaped part having 65 openings in its side wall for the reception of said conductors, an annular sharp metallic projecting edge on said part located concentrically with respect to said side wall, whereby an annular recess is provided between said edge and said side wall, a central threaded shank extending from said part, a second part having a central threaded opening to receive said shank, and a recessed projection on said second part having an annular blunt edge adapted to enter said annular recess, whereby said conductors are pressed against said sharp edge and are forced into said annular recess and wedged against said side wall when said parts are attached together.

3. A device for connecting insulated electrical 20 conductors, comprising a cup-shaped part having openings in its side wall for the reception of said conductors, a continuous sharp metallic projecting edge on said part located in spaced relation to said side wall, whereby a continuous recess is 25 provided between said edge and said side wall, a second part attachable to said first part, and a recessed projection on said second part having a continuous blunt edge adapted to enter said recess, whereby said conductors are pressed against said sharp edge and are forced into said recess and wedged against said side wall when said parts are attached together.

4. A device for electrically conducting two insulated electrical conductors, comprising a part 35 having wall portions adapted to receive the ends of said conductors, a metallic member carried by said part having sharp edge portions in spaced cooperative relation with said wall portions, whereby a recess area is provided between each 40 said edge portion and its associated wall portion, a second part attachable to said first part, and means on said second part for pressing said conductors against said edge portions and for forcing the conductors into said recess areas in wedging 45 engagement with said wall portions.

5. A device for electrically connecting two insulated electrical conductors, comprising a part having wall portions adapted to receive the ends of said conductors, a metallic member carried by 50 said part having sharp edge portions in spaced cooperative relation with said wall portions, whereby a recess area is provided between each said edge portion and its associated wall portion, a second part attachable to said first part, and 55 a projection on said second part having blunt edge portions adapted to enter said recess areas, whereby said conductors are pressed against said sharp edge portions and are forced into said recess areas and wedged against said wall portions when said parts are attached together.

6. A device for electrically connecting two insulated electrical conductors, comprising a cup-shaped part having opposed side wall portions with openings for the reception of the ends of 65 said conductors, a metallic member carried by said part having sharp edge portions in spaced cooperative relation with said wall portions, whereby a recess area is provided between each said edge portion and its associated wall portion, 70 a second part attachable to said first part, and means on said second part for pressing said conductors against said edge portions and for forcing the conductors into said recess areas in wedging engagement with said wall portions. 75

7. A device for electrically connecting two insulated electrical conductors, comprising a cup-shaped part having opposed side wall portions with openings for the reception of the ends of 5 said conductors, a metallic member carried by said part having sharp edge portions in spaced cooperative relation with said wall portions, whereby a recess area is provided between each said edge portion and its associated wall portion, 10 a second part attachable to said first part, and a projection on said second part having blunt edge portions adapted to enter said recess areas, whereby said conductors are pressed against said sharp edge portions and are forced into said 15 recess areas and wedged against said wall portions when said parts are attached together.

8. A device for electrically connecting two insulated electrical conductors, comprising a relatively deep cup-shaped part having openings in 20 its side wall near the edge thereof for the reception of the ends of said conductors, a metallic member carried by said part having sharp edge portions extending from the bottom of said part in spaced cooperative relation with the apertured 25 portions of said wall, whereby a recess area is provided between each said edge portion and its

associated wall portion, a second part attachable to said first part, and means on said second part for pressing said conductors against said edge portions and for forcing the conductors into said recess areas in wedging engagement with said 5 wall portions.

9. A device for electrically connecting two insulated electrical conductors, comprising a relatively deep cup-shaped part having openings in 10 its side wall near the edge thereof for the reception of the ends of said conductors, a metallic member carried by said part having sharp edge portions extending from the bottom of said part in spaced cooperative relation with the apertured 15 portions of said wall, whereby a recess area is provided between each said edge portion and its associated wall portion, a second part attachable to said first part, and a projection on said second part having blunt edge portions adapted to enter 20 said recess areas, whereby said conductors are pressed against said sharp edge portions and are forced into said recess areas and wedged against said wall portions when said parts are attached together.
